UNITED STATES PATENT OFFICE.

WILLIAM W. DEAN, OF CHICAGO, ILLINOIS, ASSIGNOR, BY MESNE ASSIGNMENTS, TO THE GARFORD MANUFACTURING COMPANY, OF ELYRIA, OHIO, A CORPORATION OF OHIO

SIGNALING DEVICE.

1,189,796.

Specification of Letters Patent. Patented July 4, 1916.

Application filed March 30, 1912. Serial No. 687,479.

To all whom it may concern:

Be it known that I, WILLIAM W. DEAN, a citizen of the United States, residing at Chicago, in the county of Cook and State of Illinois, have invented certain new and useful Improvements in Signaling Devices; and I do hereby declare the following to be a full, clear, and exact description of the invention, such as will enable others skilled in the art to which it appertains to make and use the same.

My invention relates to signaling devices such as are most commonly employed upon vehicles of various kinds and character and more particularly to the improvements in electrical signaling devices of this character. In the devices of this character, so far as I am aware, constructed before my invention, one of the contacts constituting a part of the electric switch controlling the motor magnet and controlled by its armature, has been mounted upon a cantilever beam. In this form of device, the severe pounding of the armature will force the free end of the beam out of position, thus changing the adjustment of the contacts. Likewise, when the beam is removed and restored, or when the adjustment of the contact is made, the relation between the two contacts will depend upon the tightness with which the screws are inserted which hold the beam upon its support. To overcome these objections, I mount this contact upon a bridge spanning the space between two posts so that both of its ends are supported, making it impossible for the armature to change its position, so that it will not at any time be necessary to remove the contact support, for the purpose of re-adjustment. Thus the contacts will stay in permanent adjustment, a great advantage where devices of this character are employed, since but few who use them are familiar with electrical apparatus.

Another object of my invention is to improve the devices of the character stated, so that the parts can be easily reached or readily removed for repairs or adjustments. For example, I mount the armature between the end of the motor and the contact carrying bridge and mount it in angular relation

with respect to said bridge in order that it may be removed without removing the bridge and changing the adjustment of the contact carried thereby.

Other objects of my invention and the invention itself will be better understood by reference to the following detailed description when taken in connection with the accompanying illustration, showing one specific embodiment of the invention, while the scope will be more particularly pointed out in the appended claims.

Figure 1 is a rear end view of a signaling device illustrating my invention, the cover having been removed. Fig. 2 is a section taken through Fig. 1, showing parts of the device in elevation. Fig. 3 is a detail.

Referring now to the drawing and to the particular form of my invention illustrated therein, at 1 I show a frame which may be substantially cylindrical as illustrated in the form shown. This frame is preferably made of material suitable for the conduction of lines of force. A sonorous member, such as a vibratile diaphragm is shown at 2, being clamped between the frame piece 1 and a front 3 which is perforated at 4, to permit the passage of sound waves through the front. A resonator 5 may be mounted in the opening 4.

The frame 1 acts as a support for the contact carrying bridge 9, which is supported therefrom, preferably by a pair of supporting posts 7 and 8, which in the form shown project from the rear of the frame, extending beyond the walls thereof and which may be, as here illustrated, integral with the frame. The frame also acts as a support for the armature 10 which may likewise be supported from a third post 6, likewise projecting from the rear of the frame, extending beyond the same, and which may be integral with said frame. This post is preferably mounted closer to one of the posts than to the other, the bridge supporting posts being preferably diametrically opposite one another. The magnets 11, are in the form shown, supported upon a web 12, and an anvil 13 is mounted upon the diaphragm in such relation to the armature that the armature may, when vibrated, pound one end of

the anvil and vibrate the diaphragm. When two magnets are used as illustrated in the drawing, an armature long enough to span the distance between the poles of these magnets is employed, and is connected by a leaf spring 14 to the post 6 by suitable fastening means, such as screws 15 and 16.

The contact spring 17 is connected to the support 6 by fastening means, such as a screw 18, and follows the movement of the armature. This spring carries a contact 19 which coöperates with a contact 20 carried by the bridge, the contacts 19 and 20 forming an electric switch which in the form shown is employed to control the circuit of the electro-magnet, and which is governed by the armature 10.

In the form shown, the contact is made adjustable and is mounted upon an adjustable screw 21, carried by the bridge 9. The bridge 9 is attached at each end to the supporting posts by suitable fastening means, such as screws 22 and 23, which are driven into the supporting posts and insulated from said bridge. A cover 25 is fastened over the rear of the signal device, covering the parts and protecting them from dirt, etc.

As far as I am aware, the contact supporting means hitherto employed, have been defective for one reason or another, and have not properly supported the rear contact so as to insure a permanent adjustment of this contact. This is a matter of some importance, since it is necessary to make a device of this kind fool proof in order to be successful. I have, therefore, devised this contact carrying bridge and firmly fastened each end of the bridge to a rigid support, so that no amount of hammering on the part of the armature can dislodge the contact from its normal position. I have also mounted the armature in angular relation with respect to the bridge. By this arrangement, one of the fastening means, such as the screw 16, may be removed and the armature swung about the screw 15 as a pivot, thus making the magnets accessible without removing the bridge and changing the position of the contacts, since the armature may be moved back and the screw 16 restored without changing the adjustment of either of the contacts 19 and 20.

I have thus illustrated apparatus embodying my invention, though I do not wish to be limited to the details of such apparatus, since numerous and extensive departures may be made therefrom without departing from the scope of the invention which is set forth in the appended claims, this embodiment being shown simply for the purpose of illustrating my invention.

I claim:

1. In an electric signaling device for use upon conveyances, the combination of a frame, a sonorous member, electric means

for controlling said member, a contact carrying bridge supported in said frame, an armature for said electric means adapted to operate said sonorous member, said armature being mounted under said bridge in acute angular relation to said bridge and means to detachably connect said armature to the frame whereby the armature can be removed from under the bridge without disturbing the latter.

2. In an electric horn for use upon conveyances, the combination of a frame, a vibratory sonorous member, electric means for controlling said member, a contact carrying bridge supported in said frame, a movable member controlled by said electric means, and mounted in said frame under said bridge and in acute angular relation with respect to said bridge and means to detachably connect said movable member to the frame whereby the movable member can be removed from under the bridge without disturbing the latter.

3. In an electric signaling device for use upon conveyances, the combination of a frame, a vibratile diaphragm associated therewith, an electro-magnet for actuating said diaphragm, a pair of contacts constituting an electric switch controlled by said magnet, and a bridge upon which one of said contacts is mounted, supported by said frame, an armature for said magnet carrying the other of said contacts supported in said frame under said bridge and in acute angular relation with respect thereto and means to detachably connect the armature to the frame whereby the armature can be removed from under the bridge without disturbing the latter.

4. In an electric horn for use upon conveyances, the combination of a frame, a vibratile diaphragm supported therefrom, a pair of electro-magnets in said frame adapted to actuate said diaphragm, a pair of contacts constituting an electric switch controlled by said magnets, a bridge supported by said frame across one end of said magnets and carrying one of said contacts, an armature extending across one end of said magnets under said bridge and in acute angular relation with respect thereto, said armature carrying the other of said contacts and means to detachably connect said armature to the frame whereby the armature can be removed from under the bridge without disturbing the latter.

5. In an electric signaling device for use upon conveyances, the combination of a vibratory sonorous member, electric means for actuating said member, a frame, supporting posts in said frame, a contact carrying bridge supported from said posts, a movable member controlled by said electric means, a support therefor supporting said movable member in acute angular relation

with respect to said bridge and means to detachably connect said movable member to said support whereby the movable member can be removed from under the bridge without disturbing the latter.

5 6. In an electric horn the combination of an electro-magnet, a substantially cylindrical frame piece within which said magnet is mounted, a plurality of supporting posts integral with said frame piece and projecting beyond one of the ends thereof, a contact supporting bridge supported from two of said posts, an armature in acute angular relation with respect to said bridge supported from another and means to detachably connect said armature to said frame whereby the armature can be removed from under the bridge without disturbing the latter.

10 7. In an electric horn, the combination of an electro-magnet, a substantially cylindrical frame piece, a plurality of posts carried by said frame piece and projecting beyond one end of the same, two of said posts being upon a diameter of said cylindrical frame, a contact supporting bridge supported by said two diametrically oppositely arranged posts, a third post on the periphery of the cylindrical frame nearer one of said first named posts than the other, an armature supported from said third post and means to detachably connect said armature to the frame whereby the armature can be removed from under the bridge without disturbing the latter.

15 8. In a signaling device adapted to be used upon vehicles, the combination of a frame, a contact carrying bridge, a support, an armature detachably supported under said bridge, a plurality of removable fastening means for fastening said armature to said support, said armature being revolvable about one of such means when the other is removed and being mounted in angular relation to said bridge whereby the armature can be removed from under the bridge without disturbing the latter.

20 9. In an electric horn, the combination of an electromagnet, a frame, a plurality of supports in said frame, a bridge supported from two of said supports and carrying a contact, an armature carrying a contact adapted to coöperate with said first named contact supported from said third support in acute angular relation with said bridge and means to detachably connect said armature to said third support whereby the armature can be removed from under the bridge without disturbing the latter.

25 10. In an electric horn, the combination of an electromagnet, a substantially cylindrical frame, a plurality of supports in said frame, two of said supports being upon a diameter of said cylindrical frame, a contact supporting bridge supported by said

two diametrically oppositely arranged supports, a third support on the periphery of the frame nearer one of said first named supports than the other, and an armature carrying a contact coöperating with the first named contact detachably supported by said third support whereby the armature can be removed from under the bridge without disturbing the latter.

70 11. In an electric horn, the combination of an electromagnet, a substantially cylindrical frame, a plurality of supports in said frame, two of said supports being located one at each end of a diameter of said cylindrical frame, a bridge connected at each end to one of said supports, a contact carrying member on said bridge intermediate its ends, a third support on the periphery of the frame nearer one of said first named supports than the other, a heavy armature substantially as long as the bridge, a spring connected to said armature, a pair of screws connecting said spring to said third support and a contact carried by said armature, one of said screws being removable and when removed said armature being revolvable upon the other screw to swing the contact carrying member of the armature from under the bridge.

75 12. In an automobile horn, the combination of a frame, a vibratile diaphragm associated therewith, an electromagnet for actuating said diaphragm, a pair of contacts constituting an electric switch controlled by said magnet, a contact carrying member supported from the frame upon which one of said contacts is mounted, an armature for said magnet carrying the other of said contacts supported in said frame under said first named contact carrying member and in acute angular relation with respect thereto, and means to detachably connect said armature to said frame whereby the armature can be removed from under the bridge without disturbing the latter.

80 13. In an automobile horn, the combination of a frame, a sonorous member, electric means for controlling said member, a contact carrying member supported in said frame, an armature for said electric means adapted to operate said sonorous member, said armature being mounted upon said contact supporting member in acute angular relation thereto, and means to detachably connect said armature to said frame whereby the armature can be removed from under the bridge without disturbing the latter.

85 14. In an automobile horn, the combination of a frame, a vibratile diaphragm, means to connect said diaphragm to said frame, electromagnetic means supported from the frame, an armature for said electromagnetic means, means to detachably connect the armature to the frame, apparatus through which the armature actuates the diaphragm

when operated by the electromagnet, an electric switch consisting of a pair of contacts controlled by said armature, a contact supporting member supporting one of said contacts, the other of said contacts being supported by the armature, and means to mount said contact carrying member in said frame in acute angular relation to the armature whereby the armature can be removed from

under the bridge without disturbing the 10 latter.

In testimony whereof, I affix my signature in the presence of two witnesses.

WILLIAM W. DEAN.
